TAKE-UP MECHANISM FOR LOOMS.

1,226,525.

Specification of Letters Patent.

Patented May 15, 1917.

Application filed May 17, 1916. Serial No. 98,201.

To all whom it may concern:

Be it known that I, LAWRENCE B. JENCKES, a citizen of the United States, residing at Worcester, in the county of Worcester and State of Massachusetts, have invented a new and useful Take-Up Mechanism for Looms, of which the following is a specification.

This invention relates to an improved take-up mechanism for looms. In the manufacture of certain kinds of heavy fabric it is desirable to weave the fabric in very long lengths which form a roll of large diameter when wound upon the cloth roll of the loom. The cloth roll and the take-up roll of the loom are commonly driven at substantially the same speed of rotation but the cloth roll is driven through frictional connections thereby permitting the take-up roll to advance a definite amount at each beat of the lay while the cloth roll advances merely enough to wind up the cloth delivered by the take-up roll, the driving connections slipping ahead during the remainder of the take-up motion. The necessary angular advance of the cloth roll naturally decreases as the diameter of the roll of cloth carried thereby increases.

When for any reason it becomes necessary to let back the cloth at the take-up roll, the cloth roll as commonly driven will be turned backward through a substantial angle. Such movement, on account of the large diameter of the roll of cloth, frequently lets back several times as much cloth from the cloth roll as is required to produce the necessary slackness at the take-up roll, thus leaving an objectionable amount of slack cloth between the take-up roll and the cloth roll.

It is the object of my invention to provide a take-up mechanism in which, upon backward movement of the take-up roll, the cloth roll will let back only the amount of cloth desired at the take-up roll, regardless of the diameter of the roll of cloth.

In the preferred form of my invention this result is obtained by the provision of a ratchet mechanism for driving the cloth roll,

through which mechanism the roll is driven forward, while the ratchet mechanism has no backward driving engagement.

My invention further consists of certain arrangements and combinations of parts which will be hereinafter described and more particularly pointed out in the appended claims.

A preferred form of my invention is shown in the drawings in which

Figure 1 is a front elevation of my improved take-up mechanism;

Fig. 2 is a right hand side elevation thereof;

Fig. 3 is a left hand sectional elevation of a portion of the driving mechanism taken along the line 3-3 in Fig. 1, and

Fig. 4 is a longitudinal sectional view taken along the line 4-4 in Fig. 3.

Referring to the drawings I have shown portions of a loom side 10, a breast beam 11 and a cross-girt 12. A take-up roll 13 and a guide roll 14 are rotatably mounted in bearings 15 and 16 respectively, said bearings being formed on a stand 18 secured at its upper end to the breast beam 11 and at its lower end to the cross-girt 12.

A driving shaft 20 is mounted in a bearing 21 on the stand 18 and in a second bearing 22 secured to the loom side 10. A ratchet wheel 23 is secured to the outer end of the shaft 20 and a driving pinion 24 is fixed to the shaft 20 between the bearings 21 and 22. The pinion 24 meshes with the intermediate gear 26, fixed to a shaft 27, rotatable in bearings 28 and 29, and having a pinion 30 secured to its left hand end. The pinion 30 engages the take-up gear 31 fixed to the take-up roll 13.

The ratchet wheel 23 is intermittently advanced by a pawl 32 mounted on an arm 33, having a bearing concentric with the shaft 20 and connected by a link 34 to any suitable portion of the loom from which a reciprocatory movement may be obtained. Backward movement of the ratchet wheel 23 is prevented by a weighted check pawl 35, pivoted at 36 to a stand 37 bolted to the outer face of the loom side 10.

By means of the mechanism thus far described the take-up roll will be advanced a definite angular amount for each feeding movement of the pawl 32.

5 The cloth roll 40 comprises an outer portion, commonly made of wood, having a square hole therein, through which extends a square rod 41, the tapered right hand end of which engages a corresponding recess in the left hand end of a short cloth roll shaft 42, Fig. 4, rotatable in a bearing 43 in the stand 18 and a bearing 44 in the bracket 37. A cloth roll gear 45 is freely rotatable upon the shaft 42 and is driven from the intermediate gear 26 through a second intermediate gear 46.

The driving connections between the cloth roll gear 45 and the shaft 42 will now be described. A ratchet wheel 47 is keyed to the shaft 42 (as clearly shown in Fig. 4) said wheel being provided with a series of ratchet teeth 48 (Fig. 3). A friction drum 50 is rotatably mounted upon the hub of the ratchet wheel 47 and a pair of driving pawls 51 and 52 are pivotally mounted within the drum 50 upon studs 53 and 54, carried thereby. These pawls are forced inward by springs 550 to engage the teeth 48 of the ratchet wheel 47.

30 A friction band encircles the drum 50, said band being formed of two parts 55 and 56 pivotally connected at 57, and adapted to be drawn into yielding engagement with the drum by means of a bolt 58 and wing nut 59 acting through a spring 60. A pair of lugs 61 and 62 project laterally from the friction member 56 and engage the two edges of a driving arm 63 projecting outwardly from the gear 45.

40 Having described the details of construction I will now point out the method of operation of my improved take-up mechanism. As previously explained, the take-up roll 13 receives a positive step by step advance 45 movement from the ratchet wheel 23. For every angular advance of the take-up gear 31 the cloth roll gear 45 is correspondingly advanced. This gear however is connected to the cloth roll shaft 42 only through the 50 friction members 55 and 56 and the friction drum 50, the friction members being positively moved through the driving arm 63 and the co-operating lugs 61 and 62.

The friction drum 50, acting through the 55 pawls 51 and 52 on the ratchet wheel 47, will advance the cloth roll sufficiently to take up the cloth delivered by the take-up roll and during the continued take-up movement of the link 34 and the pawl 32 the 60 friction members 55 and 56 will slip around the periphery of the drum 50. When it is desired to let back the cloth at the take-up roll 13, the pawls 32 and 35 are moved out

of mesh with the ratchet wheel 23 and the wheel is turned backward the necessary 65 amount to slacken the cloth at the take-up roll.

The backward movement of the take-up gear 31 is accompanied by a similar backward movement of the cloth roll gear 45, 70 as these two gears are positively connected through the intermediate gears 26 and 46 and the pinion 30. This backward movement of the gear 45 carries with it the friction members 55 and 56 and the friction 75 drum 50 but the pawls 51 and 52 act only in a forward direction and during this backward movement of the drum they snap idly over the ratchet teeth 48. There is thus no positive backward movement of the cloth 80 roll 40 but the roll is free to move to slacken the cloth at the take-up roll. When the necessary amount of cloth has been let back, no further backward movement of the cloth roll occurs and therefore there is no undue 85 slackness of the cloth between the cloth roll and the take-up roll.

Having thus described my invention it will be evident that changes and modifications can be made therein by those skilled 90 in the art, without departing from the spirit and scope thereof as set forth in the claims and I do not wish to be otherwise limited in the details herein disclosed.

What I claim is:—

1. In a loom, a take-up mechanism comprising a take-up roll, a cloth roll, a driving shaft, positive driving connections from said shaft to said take-up roll, and frictional driving connections from said shaft 100 to said cloth roll, said latter connections including a pawl and ratchet mechanism whereby the driving shaft and take-up roll may be rotated in a backward direction independently of the cloth roll.

2. In a loom, a take-up mechanism comprising a take-up roll, a cloth roll, a driving shaft, positive driving connections from said shaft to said take-up roll, and frictional driving connections from said shaft to said 110 cloth roll, said latter connections being effective to drive said cloth roll in the forward direction only.

3. In a loom, a take-up mechanism comprising a take-up roll, a cloth roll, a driving shaft, positive driving connections from said shaft to said take-up roll, and frictional driving connections from said shaft to said cloth roll, said connections including a driving gear loose on the cloth roll shaft, 120 a ratchet wheel fixed to said shaft, a friction drum rotatable relatively to said ratchet wheel and having a pawl adapted to engage the ratchet teeth, a friction band encircling said drum, and connections from 125 said driving gear to said band, whereby said

drum may be frictionally driven in both directions, but said ratchet wheel and roll shaft may be driven in one direction only.

4. In a loom, a take-up mechanism comprising a take-up roll, a cloth roll, a driving shaft, positive driving connections from said shaft to said take-up roll, and frictional driving connections from said shaft to said cloth roll, said latter connections in-

cluding a freely rotatable driving gear, a member fixed to the cloth roll shaft, and a ratchet mechanism through which said gear is effective to drive said member and shaft in one direction only.

In testimony whereof I have hereunto set my hand.

LAWRENCE B. JENCKES.
